LETOFF FOR MULTIBEAM LOOMS

Oscar V. Payne, Leicester, Mass., assignor to Crempton & Knowles Loom Works, Worcester, Mass., a corporation of Massachusetts

Application October 30, 1939, Serial No. 301,863

10 Claims. (Cl. 139—101)

This invention relates to improvements in let-offs for wide looms and it is the general object of the invention to permit a single let-off mechanism to be used with a plurality of warp beams 5 the warps of which are incorporated into the same fabric.

In wide looms such as those used by the manufacturer of paper felts it has been customary heretofore to wind the warp threads on a single beam 10 which extends across the width of the loom which in some instances may be five hundred inches or more in length. It is a difficult matter to wind beams of this length and also to handle them when they are being put into a loom. The 15 handling and winding of the warp for looms of this width would be facilitated if two or more shorter beams could be employed. With plural beams the warp threads derived from the independent beams would all be incorporated into the 20 same woven fabric and any condition causing a greater tension on the warp of one beam than that existing on the warp of another beam would produce a faulty cloth which would not hold its shape because of uneven tensions in the 25 warp threads in it.

It is an important object of my present invention to provide means by which plural warp beams can be regulated so that the tension of 30 their warps will be the same. This result I accomplish as set forth hereinafter by the use of a single let-off mechanism attached by equalizing connections to the beams, the effect of the connections being to cause the stress exerted on the warp threads by the let-off mechanism to be 35 the same in each of the comparatively short beams.

The form of let-off which I employ cooperates 40 with a movable whip roll which is moved toward the front of the loop as warp is consumed and it is then moved rearwardly by weights or the like which automatically come into action to produce rearward motion of the whip roll when the 45 warp tension reaches a given amount. It is a further object of my present invention to provide each of the comparatively short warp beams with an individual whip roll which is connected by the aforesaid equalizing connections to the let-off mechanism so that a single weight forming part 50 of the let-off mechanism may have its force exerted equally on the different whip rolls and warp threads passing over them.

The form of let-off which I use in the present instance is that shown in my Patent No. 2,184,059, which is an improvement of my prior Patent No. 2,103,821, but I wish it to be understood 55

that I am not necessarily limited to the type of let-off shown in these prior disclosures. The mounting for the whip rolls of the different beams may also be similar to that shown in my co-pending application Serial No. 279,712 but I do not wish necessarily to be limited to the use of the link suspension set forth in the last named application. Reference may be had however to these co-pending applications and the patent specified for a more detailed description of their structure and operation than is deemed necessary for a description of my present invention.

In the description to follow I have set forth two forms of the invention the preferred form 15 of which employs a cable and sheave hereinafter described. The equalizing of the forces acting on the whip roll can be effected however by means other than the cable and sheave and in the modified form of the invention I illustrate an alternative method which employs a floating lever 20 mounted on the weighted lever and attached by connectors such as rods to the mechanism which controls and also is controlled by the whip rolls. While I have shown these two means for effecting 25 equalization of the forces as mentioned I do not wish necessarily to be limited to them in the practice of my invention.

With these and other objects in view which will appear as the description proceeds, my invention resides in the combination and arrangement 30 of parts hereinafter described and set forth.

In the accompanying drawings, wherein two forms of my invention are set forth,

Fig. 1 is a plan view of the rear end of a loom having the preferred form of my invention applied thereto and showing the warp supplied by two aligned beams which supply the threads to be incorporated into the fabric being woven on the loom.

Figs. 2, 3 and 4 are detailed views taken in 35 the direction of arrows 2, 3 and 4, respectively, of Fig. 1.

Fig. 5 is an end elevation looking in the direction of arrow 5, Fig. 1.

Fig. 6 is a rear elevation of the structure shown 45 in Fig. 1.

Fig. 7 is a detailed end elevation of the let-off escapement control for the warp beam at the right end of the loom looking in the direction 50 of arrow 1, Fig. 6.

Fig. 8 is a detail plan view on enlarged scale in the direction of arrow 8, Fig. 5.

Fig. 9 is a detail elevation in the direction 55 of arrow 9, Fig. 8.

Fig. 10 is a detail plan view in the direction of arrow 10, Fig. 3.

Fig. 11 is an enlarged vertical section on line 11-11, Fig. 5.

5 Fig. 12 is a diagrammatic perspective view showing the relation between the cable, its sheave, and the several levers connected thereto, and

10 Fig. 13 is a diagrammatic elevation taken from the rear of the loom and showing the modified form of my invention.

In the detailed description of my invention I will first set forth briefly a type of letoff mechanism as illustrative of means for moving the whip roll in response to changes in warp tension 15 as shown for instance in my Patent No. 2,184,-059 and also a mounting for the whip rolls similar to that shown in another of my co-pending applications Serial No. 279,712.

20 Referring to the drawings, particularly Figs. 1, 6 and 7 I have shown a loom frame 10 at the rear of which in the present instance is mounted two separate horizontally aligned warp beams 11 and 12 located respectively at the right and left hand ends of the loom as viewed from the rear and having a fixed common center bearing b. These beams supply respectively warp threads W and W' which lead upwardly over warp rolls 13 and 14, respectively, and thence to the forward part 25 of the loom for the production of warp sheds through which the shuttle not shown is picked. Movement of the warp beams in a direction to feed the warp threads W and W', and also the forward and backward motions of the whip rolls toward and from the front of the loom are regulated by a letoff mechanism designated generally at L, see more particularly Figs. 6 and 7. Parts of this mechanism are duplicated at both ends of the loom, the mechanism L being adjacent the beam 11 while a similar mechanism L' is adjacent 30 the beam 12. Since these mechanisms L and L' are similar to each other I will give a detailed description of but one of them.

40 The gudgeon 15 of warp beam 11 has mounted thereon a gear 16 meshing with a pinion 17 fast 45 with a larger gear 18, both of these parts being secured to and rotating with a shaft 19 supported in a housing 20. Gear 18 meshes with a pinion 21 secured to a shaft 22 and rotating with a gear 23 also secured to shaft 22 and meshing with a pinion 24 secured to an escapement shaft 25 to which is also secured an escapement wheel 26. The latter cooperates with an escapement pawl 27 pivoted at 28 with respect to the housing 20 and having fingers 29 and 30 which move with 50 respect to the escapement wheel in such a way that when the pawl rocks in one direction one of the fingers moves out of engagement with one of the escapement teeth 31 and the other finger enters a notch between two adjacent teeth on the escapement wheel. In this way oscillation of the pawl about its pivot permits rotary motion of the escapement wheel.

55 The pawl is restrained by a brake lever 32 pivoted as at 33 on the housing 20 and having pivoted at the left end thereof as viewed in Fig. 7 a brake shoe 34 for engagement with an arcuate brake rim 35 formed on the pawl. When the shoe is in engagement with the rim the pawl is 60 locked against oscillation and the escapement wheel and the gearing connected thereto are held against rotation to hold the beam against rotation. When the shoe moves away from the rim 35, however, the tension of the warp thread tends 65 to rotate the gear 16 in the direction of arrow a.

Fig. 7, and urges the escapement wheel to rotate and effect oscillation of the pawl.

The mechanism for controlling the brake lever 32 includes a rod 36 passing through the right arm 37 of lever 32 and having a stop collar 38 fixed thereto under the arm 37. A compression spring 39 surrounds the rod 36 and extends upwardly from the lever to a sleeve 40 loosely surrounding the rod and having its upper position determined by an adjusting nut N. The upper 10 end of the rod is pivoted to a bell crank lever 41 pivoted with respect to the loom frame at 42 and having an upwardly extending arm 43 pivotally connected to a rod 44 extending to the left as viewed in Fig. 1 to a pressure lever 45 moving 15 about a fixed pivot 46, see Fig. 1. An arm 47 of the lever 45 extends laterally and bears against a lug 48 to be further described and moving with whip roll 13.

20 From the matter thus far described it will be apparent that forward motion of the whip roll 13 due to tightening of the warp passing over it will rock lever 45 in a counter-clockwise direction to pull rod 44 to the left and raise rod 36 the effect of which is to move the shoe 34 away from the 25 rim 35 and allow the pawl to oscillate with resultant forward feeding of warp from beam 11. When the beam turns to feed warp forwardly pressure on the whip roll is slackened, and by means of weighted mechanism to be described 30 hereinafter the lever 45 is acted upon to turn in a clockwise direction as viewed in Fig. 1 to exert a rearward force on lug 48 the effect of which is to move the whip roll 13 rearwardly. During this last named turning of lever 45 rod 36 will descend 35 and ultimately effect engagement between the shoe 34 and the rim 35 to lock the pawl and arrest further rotation of the warp beam for the time being.

40 The matter thus far described relates to the let-off mechanism and is similar to the structure set forth in my copending application Serial No. 254,441 to which reference may be had for a further description of its structure and operation. It is also to be understood that the let-off design- 45 ated at L' at the left end of Fig. 6 is similar to the mechanism set forth in Fig. 7 and operates in a very similar manner through a rod 50 connected at its upper end to a lever 51 moving about a fixed pivot 52 and connected to a rod 53 at- 50 tached to a lever 54 moving about a fixed pivot 55 and similar to lever 45 in that it exerts rearward force on a lug 56 moving with the left end of whip roll 14. It will therefore be seen that rocking of lever 54 in a left hand direction when beam 55 14 moves forwardly due to warp tightening will lift rod 50 to let-off of warp from beam W'.

As previously intimated the whip rolls are movable backwardly and forwardly in response to variation in tension of the warp threads passing 60 over them. Horizontal motion of the whip rolls may be provided for by the mountings shown for instance in my co-pending application Serial No. 279,712, and I will describe these mountings with respect to roll 13 with the understanding that 65 whip roll 14 has the same kind of mounting.

70 Referring particularly to Fig. 1, a bracket 60 is secured to the left end of the roll 13 and carries a vertical pivot pin 61 for a link 62. The latter is pivoted as at 63 to a second link 64 moving 70 about a fixed vertical pivot 65 carried by a stationary support 66 forming part of the loom frame. The pivots 61, 63 and 65 are relatively large and sufficiently strong to support the whip roll for movement in a horizontal direction. 75

The right end of whip roll 13 is provided with a roller bearing support designated generally at R, see Figs. 1 and 5. This support includes a foot 70 having depending rails 71 which are vertically above other rails 72 carried by a stationary support 73. Between each pair of rails 71 and 72 is located a roller bearing in the form of a chain C having rolls 74 between the upper and lower rails and having side links 75 which connect the rolls 74 together and also engage the sides of the rails 71 and 72 to prevent objectionable lateral motion of whip roll 13 in the direction of a length thereof. The foot 70 carries a previously described lug 48 which cooperates with lever 45 as already described. The mounting for the left end of whip roll 14 is similar to that already described in connection with the right end of whip roll 13, the previously described lug 56 being carried by a foot 76 similar to foot 70 resting on structure corresponding to that already described in connection with foot 70.

The link support for the adjacent ends of the whip rolls 13 and 14 are associated with levers 67 and 68, respectively, movable about fixed pivots 69 and exerting rearward force on the bracket 20 through an adjusting screw 71.

For a more detailed description of the mounting for the ends of the whip rolls reference may be had to my co-pending application Serial No. 279,712 and it is thought sufficient for present purposes to state that the whip rolls are mounted to move toward and from the front of the loom and that forward motion of whip roll 13, for instance, is associated with a counter-clockwise rocking of levers 45 and 67 when the warp threads become tight and that the whip roll is moved rearwardly by pressure exerted by these levers 45 and 67 when they are turned in a clockwise direction by a weight to be described. Similarly whip roll 14 moves in response to warp tightening to effect rocking of levers 54 and 68 and is likewise movable rearwardly by a rocking of these last named levers in the opposite direction.

As previously stated the warps W and W' are destined for incorporation into a single factor and the tensions on these two systems of warp threads should therefore be equalized so that the resultant fabric will be free from internal strains such as would result if one set of warp threads were tighter than the other. In my Patent No. 2,184,059 there is shown a weight which is raised when the whip roll moves forwardly due to tightening the warp threads, this weight being released when the escapement pawl is unlocked and effective to move the whip roll rearwardly. I use a similar weight in the present instance but instead of having an individual weight for each of the two let off mechanisms L and L' which might result in uneven control of the whip rolls 13 and 14 I employ a single weight and connect it to the structure already described in such a way as to equalize the forces exerted on the two whip rolls.

In carrying the preferred form of my invention into effect I provide a lever 80 moving about a fixed pivot 81 and having a horizontal arm 82 which supports a variable weight 83 at different distances from the pivot 81. A vertical arm 84 of lever 82 carries a sheave 85 turning on a stud 86 on the arm. Trained around this sheave 85 is a flexible cable 87 the upper section 88 of which controls the whip roll 14 while the lower section 89 thereof controls the whip roll 13.

The left end of the upper section 88 of the cable is connected as at 90 to lever 54 at the

left end of the loom as viewed in Fig. 1 and this section is also connected to lever 68 by a head 91 pivoted to the lever 68 and having the cable secured thereto. The left end of the lower section 89 of the cable is connected as at 95 to lever 67 and has also a head 96 similar to head 91 connected to lever 45 at 97.

In operation, the warp will be consumed during normal weaving operations in the usual manner. When the beams are locked against rotation the continuing demand for warp threads will be met by forward motion of the whip rolls. When the whip rolls move forwardly they act through lug 48, screws 71 and lug 56 to turn the levers 45, 67, 68 and 54, respectively in a counterclockwise direction, see Fig. 1. The left ends of both cable sections 88 and 89 will move to the left as will also sheave 85 with resultant lifting of the weight 83. Levers 45 and 54 will raise rods 36 and 50, respectively, to release the escapement mechanism lock shoes 34 at both ends of the loom, whereupon the beams turn due to the force exerted on them by the warp threads. As the warp is fed from the beams the pressure exerted on the whip rolls is reduced and the latter are moved rearwardly by a right hand angular motion of levers 45, 67, 68 and 54 induced by weight 83. This rearward motion of the whip rolls is accompanied by motion of the cable sections 88 and 89 to the right, Fig. 1, and the lever 84 is therefore temporarily free to rock in a right hand direction as viewed in Fig. 6 under action of the weight 83. The right hand rotation of levers 45 and 54 results in lowering their respective rods 36 and 50 which ultimately causes shoes 34 to engage rims 35 to stop further rotation of the beams. This operation occurs repeatedly during the running of the loom. The whip rolls advancing when the warp beams are tight to effect unlocking of the escapement, and then moving rearwardly under action of the weight 83 when the beam is unlocked and turns to supply warp.

If the condition of beam 11 should be such that a given angular movement thereof would supply more than the same angular movement of beam 12, whip roll 13 would move rearwardly at a faster rate than would whip roll 14 with the result that the escapement corresponding to beam 11 would be locked before locking of the escapement for beam 12. The latter escapement would therefore continue to oscillate after beam 11 had been locked, since the locking of each escapement depends upon the position of the corresponding whip roll. When beam 11 is locked rearward motion of the whip roll 13 ceases and therefore the lower strand or section 89 of the cable becomes temporarily stationary. Under the assumed condition whip roll 14 will continue to move rearwardly and the upper strand 88 of the cable continues to move to the right due to the fact that sheave 85 is free to turn on lever 84 and the latter continues to rock in a right hand direction because of weight 83. When beam 12 is ultimately locked whip roll 14 comes temporarily to rest and then starts forward with whip roll 13 which has already started to advance. Cable strands 88 and 89 therefore move to the left due to advance motion of the whip rolls and there is a corresponding lifting of weight 83.

If whip roll 14 should move forward at a rate faster than that of whip roll 13, the escapement for beam 12 will unlock while the escapement of beam 11 is still locked and whip roll 14 will start

to move rearwardly. Under these conditions the upper strand 88 of the cable will move to the right under action of weight 83 while the lower strand will be held against motion to the right and will 5 actually be moving to the left because whip roll 13 is still advancing. Whip roll 14 therefore starts to move rearwardly while whip roll 13 is advancing and the escapement at the left end of the loom will be locked when the whip roll 14 reaches a predetermined rearward position regardless of the motion of whip roll 13.

The corresponding arms of the levers 45, 67, 68 and 54 are substantially equal so that the forces exerted on the whip rolls 13 and 14 by the single 15 weight are substantially the same. I do not deem it essential that all of the levers just mentioned shall be of the same size, but the proportions of the levers should be such that the forces exerted on the whip rolls will be equal.

20 I am not limited to the use of a cable and a sheave as shown in the preferred form of the invention already described and where it is desired to use rigid connections I may employ the modified structure set forth diagrammatically in 25 Fig. 13. It is to be borne in mind that the whip rolls move back and forth through a comparatively short distance between locking and unlocking positions for the letoff and for this reason I can use a floating lever 100 pivoted as at 101 30 to a lever 102 which corresponds to lever 80 in the preferred form. As shown in Fig. 13 the upper arm 103 of lever 100 is connected to a rod 104 extending to the left and attached by means of a rod head 105 to a lever 106 corresponding to 35 lever 68. From the rod head 105 a second rod 107 extends to the left to be connected as at 108 to a lever 109 corresponding to lever 54. Levers 106 and 109 have force communicating connections with the whip roll 14 at 110 and 111, respectively, in a manner similar to that of the preferred form.

The lower arm 115 of lever 100 is attached to a 40 rod 116 connected to a rod head 117 pivoted on a lever 118 corresponding to lever 45 already described, and a rod 119 extending to the left from the rod head 117 is connected as at 120 to a lever 121 corresponding to lever 67. Levers 118 and 121 have force transmitting connections 122 and 123, respectively, with the whip roll 13.

45 The operation of the modified form is quite similar to that already described in connection with the preferred form. When the whip rolls move forwardly the levers 106, 109, 118 and 121, are rocked in a counter-clockwise direction and therefore exert left hand pulls on the rods attached to them, with the result that the floating lever 100 is moved to the left and the lever 102 is turned in such a direction as to raise a weight 125 corresponding to weight 83. On the other 50 hand, when the whip rolls have reached their forward position and have effected unlocking of their respective letoff mechanisms, the lever 102 turns to the right to exert a force on the rods 104 and 116 and also on rods 107 and 119 directed 55 to the right and tending to rock the levers connected to the rods in a right hand direction and cause rearward movement of the whip rolls.

50 Should either whip roll in the modified form move at a rate different from that of the other whip roll, or move in a direction opposite to the motion of the other whip roll, the operation will be substantially the same as that already described for the preferred form, the essential difference being that in the modified form the lever 100 will rock on its pivot 101 whereas in the

preferred form the sheave would rotate. As will be apparent from Fig. 13 whip roll 13 may move forwardly to cause left hand motion of arm 115 while whip roll 14 can move rearwardly, which corresponds to a right hand motion of arm 103. 5 The weight 125 acts constantly to keep the connections between lever 102 and the whip rolls tight and in force transmitting relationship.

Fig. 13 has been restricted to the changes necessary to use rigid rods as substitutes for the 10 cable and a lever as a substitute for the sheave in the preferred form, but it is to be understood that the connections to the letoff mechanisms will be the same as in the preferred form, levers 109 and 118 controlling, respectively, the letoffs for 15 the left and right hand sides of the loom.

A feature to be noted in connection with the modified form of the invention is that levers 106 and 109 need not necessarily be the same as levers 118 and 121. In fact, the ratio of the arms for 20 the levers of the left hand whip roll 14 can be different from the ratios of the arms for the other whip roll 13, the difference in ratio being made up by the difference in length of the arms 103 and 115 of the lever 100. 25

From the foregoing it will be seen that I have provided a simple control for two independently acting letoff mechanisms for two separate beams, whereby each beam and its whip roll can move in response to variations in warp tension of the 30 associated system of warp threads independently of the mechanism acting on the other system of warp threads. Also, uniformity of tension is insured because both systems are acted on by the same weighted member. The levers which control and in turn are controlled by the whip rolls are so proportioned that the weight 83 exerts equal restraining forces on the whip rolls when the latter advance, and exert equal actuating forces on the rolls when the latter are to be 40 moved rearwardly. It will also be seen that the principles of my invention and the advantages to be derived from it can be achieved as set forth in the modified form of the invention by a floating lever mounted on the weighted member and 45 having rigid connectors extending to the various levers which are moved by and in turn effect movement of the whip rolls.

Having thus described my invention it will be 50 seen that changes and modifications may be made therein by those skilled in the art without departing from the spirit and scope of the invention and I do not wish to be limited to the details herein disclosed, but what I claim is:

1. In a loom having a pair of warp beams each 55 to supply a part of the warp to be incorporated into a single fabric being woven by a loom, the loom having a whip roll for each beam movable independently of the whip roll for the other beam and having a letoff mechanism for each beam capable of locking and unlocking the corresponding beam, and having connections between each whip roll and the corresponding letoff mechanism by which the latter is unlocked to permit rotation of the associated warp beam when the corresponding whip roll is forward and by which the letoff is locked to prevent rotation of the associated warp beam when the corresponding whip roll is rearward, that improvement which 60 comprises a single weighted member for both whip rolls, and equalizing connections between the weighted member and the two whip rolls to cause the weighted member to exert the same resisting force on each whip roll when the latter tends to 65 move forwardly and causing the weighted mem- 70 75 75

- ber to exert the same force on each whip roll to move the latter rearwardly.
2. In a loom having a pair of warp beams each to supply a part of the warp to be incorporated into a single fabric being woven by a loom, the loom having a whip roll for each beam movable independently of the whip roll for the other beam and having a letoff mechanism for each beam capable of locking and unlocking the corresponding warp beam, and having connections between each whip roll and the corresponding letoff mechanism by which the latter is unlocked to permit rotation of the associated warp beam when the corresponding whip roll is forward and by which the letoff is locked to prevent rotation of the associated warp beam when the corresponding whip roll is rearward, that improvement comprising a single weighted member for both whip rolls requiring the application of force thereto to be moved in one direction and tending constantly to move in the opposite direction, a connection from each whip roll to the weighted member by which each whip roll tends to move the weighted member in said one direction when moving forwardly and by which the weighted member exerts a force in the said opposite direction tending to move the whip roll rearwardly, and an equalizer between the connections and the weighted member to cause the latter to exert equal forces on the connection.
3. In a loom having a pair of warp beams each to supply a part of the warp to be incorporated into a single fabric being woven by a loom, the loom having a whip roll for each warp beam movable independently of the whip roll for the other warp beam and having a letoff mechanism for each warp beam capable of locking and unlocking the corresponding beam, and having connections between each whip roll and the corresponding letoff mechanism by which the latter is unlocked to permit rotation of the associated warp beam when the corresponding whip roll is forward, and by which the letoff is locked to prevent rotation of the associated beam when the corresponding whip roll is rearward, that improvement comprising a single weighted member for both whip rolls requiring the application of force thereto to be raised and tending constantly to move downwardly, connections between the whip rolls and the weighted member by which each whip roll tends to raise the weighted member when moving forwardly and by which the weighted member in tending to move downwardly tends to exert a force acting to move the whip roll rearwardly, and an equalizer in the connections between the whip rolls and the weighted member to cause the latter to exert equal forces on the whip rolls.
4. In a loom having a pair of independently rotatable warp beams and having a movable whip roll for each beam, a letoff mechanism for each beam to be locked to prevent turning of the corresponding beam by movement to a given rearward position by the associated whip roll and to be unlocked to permit turning of the warp beam by forward movement to a predetermined forward position by the whip roll, that improvement which comprises a single weighted member for both letoff mechanisms, and equalizing connections between both whip rolls and the single weighted member, the weight acting through said connections to exert equal forces on the whip rolls tending to move the latter to said given position and said connections tending to raise the weighted member when either whip roll moves forwardly.

5. In a loom having a pair of independently rotatable warp beams and having a movable whip roll for each beam, a letoff mechanism for each beam to be locked to prevent turning of the corresponding beam by movement to a given rearward position by the associated whip roll and to be unlocked to permit turning of the warp beam by forward movement to a predetermined forward position by the whip roll, that improvement which comprises a single weighted member for both whip rolls, a pulley moving with and rotatable relatively to the weighted member, a cable the intermediate part between the ends of which is trained around the pulley, and means to connect one end of the cable to one whip roll and the other end of the cable to the other whip roll, motion of either whip roll toward the predetermined forward position being resisted by the single weighted member by a force transmitted through the cable, and the weighted member acting through the cable to move either whip roll toward the given rearward position.

6. In a loom having a pair of independently rotatable warp beams and having a movable whip roll for each beam, a letoff mechanism for each beam to be locked to prevent turning of the corresponding beam by movement to a given rearward position by the associated whip roll and to be unlocked to permit turning of the warp beam by forward movement to a predetermined forward position by the whip roll, that improvement comprising a lever for each letoff mechanism movable in one direction to lock the corresponding warp beam, a single weighted member, flexible equalizing connections between the single weighted member and each whip roll to transmit a force from the weighted member to either roll to resist forward movement thereof and transmitting a force from each whip roll when the latter moves forwardly to the weighted member tending to raise the latter, and a connection between each whip roll and the corresponding lever to move the latter to unlock the letoff connected thereto when the corresponding whip roll moves forwardly to said predetermined position and to move the lever in the opposite direction when the corresponding whip roll moves rearwardly to said given position to lock the letoff mechanism connected thereto.

7. In a loom having a pair of independently rotatable warp beams and having a movable whip roll for each beam, a letoff mechanism for each beam to be locked to prevent turning of the corresponding beam by movement to a given rearward position by the associated whip roll and to be unlocked to permit turning of the warp beam by forward movement to a predetermined forward position by the whip roll, that improvement comprising a single movable weighted member for both whip rolls, connections between the whip rolls and the weighted member including elements extending from the weighted member toward each whip roll, and movable with and by the weighted member and the whip rolls, means connecting each whip roll and the element corresponding thereto to cause each whip roll when moving forwardly to exert a force through the associated element on the weighted member tending to lift the same, and each element transmitting a force from the weighted member through the corresponding means tending to cause rearward movement of the associated whip roll, and an equalizer connecting the elements to the weighted member and acting to cause the latter to exert equal forces on the elements and acting to cause

either element to lift the weighted member when moving toward said predetermined forward position.

8. In a loom having two independent warp beams each supplying part of the warp thread which is incorporated into the fabric being woven in the loom, a let off mechanism for each warp beam, each let off mechanism capable of locking the beam corresponding thereto against rotation and also capable of releasing the corresponding beam to permit rotation thereof due to tension of the warp thereof, a whip roll for each warp beam, the warp thread of each beam extending over the corresponding whip roll and tending to move the latter forwardly when the associated warp beam is locked against rotation, control connections between each whip roll and the let off mechanism corresponding thereto to unlock the associated beam when the corresponding whip roll reaches a given forward position, a single weighted member for both whip rolls, a train of mechanism extending from each whip roll toward the weighted member, equalizing connections between said trains of mechanism and the weighted member to cause the latter to exert equal forces on the train, each whip roll when moving forwardly acting through the train corresponding thereto to exert a lifting force on the weighted member through the equalizer, and the weighted member acting through the equalizer and the train of a whip roll which is in said given forward position tending to move the latter rearwardly to tension the warp of the corresponding warp beam during rotation of the latter due to releasing thereof by the associated let off mechanism.

9. In a loom having two separate warp beams each supplying a part of the warp thread to be incorporated in the fabric being woven by the loom, a whip roll for each beam, a let off mechanism for each beam controlled by movement of the corresponding whip roll, the warp thread of a beam extending over the corresponding whip roll and tending to move the latter forwardly, means controlled by each whip roll when in a given rearward position to cause the let off mechanism corresponding thereto to lock the associated warp beam against rotation, other means to cause each whip roll to unlock the corresponding let off mechanism to permit the associated warp beam to turn under tension of the warp thread thereof when the whip roll reaches a predetermined forward position, a single weighted member for both whip rolls, a train of mechanism extending from each whip roll toward the weighted member, an equalizer between the trains of mechanisms and the weighted member to cause the

latter to exert equal forces on the trains, the whip roll of a warp beam which is locked moving toward said predetermined forward position under action of the warp thread extending thereover and acting through the corresponding train and the equalizer to lift the weighted member, and the weighted member acting through the equalizer and the train of a whip roll which has reached said predetermined forward position effective to move the whip roll toward said given rearward position during rotation of the associated warp beam, each whip roll movable toward and from said given rearward and predetermined forward positions independently of the other whip roll and the equalizer being capable of transmitting a lifting force on the weighted member from one of said trains when the corresponding whip roll is moving forwardly and simultaneously transmit a force from the weighted member to the other whip roll tending to move the latter rearwardly.

10. In a loom having a pair of independently rotatable whip rolls each supplying a part of the warp thread to be incorporated into the fabric being woven by the loom, a let off mechanism for each beam, each let off mechanism capable of locking the corresponding beam to prevent rotation of the latter and capable of unlocking the corresponding beam to permit rotation of the latter due to tension of the corresponding warp thread, a whip roll for each beam, each whip roll movable forwardly to a predetermined position by tension of the corresponding warp thread when the associated warp beam is locked, means operated by each train when the corresponding whip roll reaches said predetermined position to cause the corresponding let off to unlock the associated warp beam, a single weighted member, a train of mechanism for each whip roll extending toward the weighted member, an equalizer connecting the trains of mechanism and the weighted member to cause the latter to exert equal forces on the trains, each whip roll when moving to said predetermined position having the forward motion thereof resisted by the weighted member acting through the equalizer and the corresponding train, each train capable of transmitting a lifting force from the corresponding whip roll to the weighted member through the equalizer when the associated warp beam is locked, and each train transmitting a force from the weighted member through the equalizer to the corresponding whip roll tending to move the latter rearwardly when the associated warp beam is unlocked.
